HORIZONTAL POT TYPE BURNER

Bruce Hayter, Santa Fe, N. Mex., and Stanley Perry, Chicago, Ill., assignors to Oil Devices, Santa Fe, N. Mex., a limited partnership of Illinois

Application March 25, 1943, Serial No. 480,450

11 Claims.

(Cl. 158—91)

Our invention relates to an improvement in horizontal pot type burners and has for one object to provide an improved means for subjecting the fuel of a pot type burner to heat of combustion in order to vaporize the fuel.

Another object of the invention is to provide an improved means for delivering a liquid fuel to the pot.

Another object is to provide improved means for heating the vaporizing cup.

Another object is to provide an improved vaporizing cup structure.

Another object is to provide a vaporizing cup with an increased vaporizing capacity.

Another object is to provide improved means for conducting the heat of the flame to the vaporizing cup.

Other objects will appear from time to time in the course of the specification.

Our invention is illustrated more or less diagrammatically in the accompanying drawings, wherein:

Figure 1 is a plan view;

Figure 2 is a section along the line 2—2 of Figure 1;

Figure 3 is a section along the line 3—3 of Figure 2;

Figure 4 is a bottom plan view of the cup shown in Figures 2 and 3;

Figure 5 is a section similar to Figure 3, showing a variant form of cup;

Figure 6 is a bottom plan view of the cup shown in Figure 5;

Figure 7 is a view similar to Figure 5 illustrating a further form of cup;

Figure 8 is a bottom plan view of the cup shown in Figure 7; and

Figure 9 is a more or less diagrammatic illustration of the unitary control of motor, fuel supply and tertiary air.

Like parts are indicated by like characters throughout the specification and drawings.

Referring to the drawings, 1 indicates generally any suitable heater structure or flame receiving member, the details of which do not form part of the present invention. It is provided with an aperture 2 for admitting the flame and exhaust gases from the burner. 3 is any suitable exterior abutment plate which may be secured to the member 1, in any suitable manner as, for example, by bolts 4. The plate 3 may serve as a supporting means for the burner unit as a whole. Mounted on this base plate 3 is a ring 5, having an annular flange 6 aligned with the aperture 2 and herein shown as having its inner lip 7 spaced within

and terminating in the general plane of the edge 8 of a generally central aperture in the base plate 3. It may be removably mounted on the base plate 3 by any suitable spacers 9 and bolts 9—a. 5 For example, we may employ spacers 9 and bolts 9—a extending therethrough outwardly from the base plate 3 through any suitable ears or enlargements of the ring 5. Securing nuts may be employed. The entire assembly can be removed as a unit from the base plate 3. It may be observed that air may flow along the path indicated by arrows at the top of Figure 3 and may enter through the aperture between the flange 6 and the base plate 3.

15 Secured to the ring 5 is an outer housing 10, herein shown as cylindrical and as having an end 11 with the generally central aperture 12. 13 generally indicates the burner pot proper with a bottom or end 14. Its generally cylindrical but 20 slightly tapered wall is provided with a plurality of primary air inlets 15. Similar inlets could, if desired, be employed in the end of bottom wall, and it will be understood that substantial variations of size, spacing and arrangement of primary 25 air inlet apertures may be employed.

Secondary air may be admitted through a row of larger and more closely spaced secondary air inlet apertures 16 located adjacent the ring 5. It will be understood that the inner portion of 30 the ring 5 operates as a flame ring and is provided with a central aperture 17 aligned with the corresponding apertures in the member 1 and the base ring 3. We may, if desired, employ a recirculating ring 18, herein shown as mounted on 35 the flame ring 5 by any suitable spacers 19 and securing members 20. The inner edge of the flame ring is spaced inwardly from the wall of the pot 13. The flame ring has a central aperture 21 of about the same diameter as the aperture 17 of the flame ring and preferably axially aligned therewith. We illustrate the outer row of 40 primary air inlet apertures 15 as partially masked by a deflector 22 which directs air from this row upwardly across the path of delivery of air 45 through the secondary air inlets 16. 23 indicates a shield or baffle secured to the bottom or end 14 of the pot in line with the delivery of air thereagainst by a fan 24 actuated by any suitable motor 25 mounted by bracket means 26 on the 50 removable ring 27 secured to the bottom or end 11 of the outer housing 10. The diameter of the fan 25 is preferably such that it may pass through the aperture 12 in the bottom or end member 11. The shield is in the form of a flat disk which 55 may be centrally welded or otherwise secured to

the bottom or end of the pot 13. Portions of the edge of the disk are inwardly bent, to provide spacing abutments for engaging the bottom of end of the pot. 28 is any suitable guiding means for directing air forwardly through the space between the pot 13 and the outer housing 10.

Mounted on the outer housing 10 by any suitable bracket or support 30 is any suitable fuel control means such as the float chamber 31, with any suitable valve control handle 32. The details of the float chamber and valve do not of themselves form part of the present invention but it will be understood that a liquid fuel may be delivered to the float chamber from any suitable source and that the float chamber serves to control the level of the fuel in the below described vaporizing cup 42. 33 indicates any suitable duct or pipe extending to a sump element 34 located beneath the lower side of the housing 10. 35 indicates any suitable union member screw threaded at its lower end as at 36 and at its upper end as at 37. The sump may be screw threaded upon the lower portion 36. 38 is any suitable lock nut also screw threaded upon the portion 36. 39 is any suitable spacer surrounding the union 35 and interposed between the members 10 and 13. 40 is a cup stem internally screw threaded at its lower end, and secured upon the screw threaded portion 37 of the union 35. It has an inner bore 41 extending to its upper end and is expanded at its upper end to form a cup 42. It will be understood that the relation between the level of fuel in the cup 42 and the level of the fuel in the float valve structure 31 is such that the level of liquid fuel in the bottom of the cup 42 may be controlled by the setting of the valve control element 32. Surrounding the cup 42 is an outwardly extending horizontal flange 43 which is cut away at one edge as at 44, the cut away portion being that most closely adjacent the recirculating ring 18 and the flame ring. Extending downwardly from the bottom of the cup 42 and preferably formed integral with it and the stem 40 are a plurality of vanes 45.

In order to light the fuel, a lighting aperture is provided. We illustrate for example, a ring in the upper side of the pot 13, indicated at 48. In line with the ring, the outer housing 10 is apertured as at 49. Any suitable closure plug 50 may be employed which rests gravitally against the upper surface of the ring 48 in a firm closing relationship. The plug is also provided with a downwardly extending portion 51 of reduced diameter which more or less snugly fits the aperture of the ring 48. The plug may be held against loss by any suitable securing means 52.

In the variant form of Figures 5 and 6, we use a cup 42a with a vaporizing dead end passage 60. This passage extends generally axially through the apertures of the rings 5 and 18 and therefore extends along the line of movement of the flame at intermediate or high fire. A lip 61 prevents the access of liquid fuel to the passage 60, unless the depth of the fuel in the cup rises up over the level of the lip. Thus the vaporizing passage does not operate at pilot flame or at low fire except as a heat conductor to the cup. At high fire, it serves as a means of increasing or adding to the vaporizing capacity of the cup. The liquid flowing into the passage 60 is subjected to the maximum heating effect of the flame or exhaust gases flowing outwardly through the above mentioned apertures.

In the form of Figure 7, we illustrate a variant

type of cup 75 having the circumferential outwardly extending flange 76. Fins 77 are employed similar to the fins 45 of the form of Figure 3. Instead of the hollow passage 60, this form has an extension generally indicated as 78 which extends through the central aperture of the flame ring 5. This extension 78 also may have upper and lower ribs 79, 80, respectively.

We illustrate in connection with the form of Figure 7, means for controlling the tertiary air. It will be understood, however, that the same control means may also be employed with the other forms of the invention. The tertiary air supply means includes any suitable tertiary air box 85 with a delivery lip 86 defining an annular passage 87. Air may be admitted to the tertiary air box through any suitable aperture 88 controlled by the tertiary air shutter 89 which may, for example, be pivoted as at 90. Any suitable means may be employed for controlling 89 in unison with the manual oil control. There is illustrated for example in the diagrammatic Figure 9, the motor 25 with any suitable circuit 25a therefor. This circuit may be controlled by a rheostat 25b which in turn is controlled by rotation of the manual control handle 32a which simultaneously operates the oil control handle 32b. Any suitable connection for actuating the tertiary air shutter 89 may be employed including for example, the linkage 95 between the shutter and the oil control member 32b. This means is shown diagrammatically but it will be understood that a variety of means may be employed for varying the movement of the tertiary air shutter in response to the movement of the oil control member. Thus there is a simultaneous control of the air supplying motor 25, the oil flow controlling member 32b, and the tertiary air control shutter 89.

The use and operation of our device are as follows:

In the present burner, which is of the hydroxylating type, primary air is delivered to the interior of the pot 13 through primary air inlet apertures 15. We may use natural draft or we may use fan means, such as the fan 24, to cause the air to flow into the pot. A liquid fuel is delivered to the bottom of the cup 42 along the passage 41. Once combustion has been initiated, the fuel is vaporized by the heat of combustion in or adjacent the pot, and the vaporized hydrocarbon mingles with the primary air to produce a primary, partially combustible mixture. This mixture is directed, either under natural draft, or by the fan 24, through the central aperture of the flame ring 5 and into the interior of the member 1. At high fire, a flame is delivered horizontally to a substantial distance. The cup is adequately heated by combustion going on about it, and vaporization of the fuel is efficiently maintained. The secondary air needed to produce the final combustible mixture is delivered through the apertures 16 and through the upper or inner row of apertures 15, within the deflector 22. As the secondary air joins with the primary mixture, a completely combustible mixture is formed, and the flame of this combustible mixture extends into the interior of the member 1. The space between the base member 3 and the flange 6 serves for the admission of additional tertiary air, which prevents smoking and completes the combustion of all or substantially all of the carbon delivered into the interior of the member 1.

At the lower stages of combustion, a much smaller rate of flow is maintained to the cup 42.

Combustion takes place at or above the lip of the cup and more or less around the sides of the cup. In order to adequately heat the cup, it is important that this heat of combustion be adequately conducted to the cup and particularly to the bottom of the cup. The stem 40, the side flange 43, which is preferably more or less thickened as shown in Figure 3, and the vanes 45, all assist in conducting to the cup the heat of combustion going on about it, and the result is the maintenance of the cup at adequate temperatures to vaporize the inflowing hydrocarbon even when the rate of flow may be substantially reduced.

In the present burner, it is important that the liquid fuel supplied to the vaporizing cup be completely consumed. The cup must be hot enough for complete vaporization and the less volatile portions of the fuel must be consumed or reduced to a powder or light ash. This is particularly the case when relatively heavy fuels such as Diesel oil are burned.

In the form of Figures 1 to 4, we illustrate a vaporizing cup having a plurality of heat conducting flanges and vanes. The vanes serve to conduct the heat of combustion to the cup and to maintain the cup at a sufficiently high temperature to effect complete vaporization of the fuel, even at the pilot stage.

The form of Figures 5 and 6 illustrates the employment of a supplemental vaporizing chamber extending along the path of flow of the hot gases and flame. If the liquid level in the cup gets high enough to flood over the lip 61, the liquid fuel is then heated within the chamber 60 to a temperature high enough, rapidly and completely, to vaporize it. In effect, the capacity of the cup is increased when the volume of flow is increased. The member 60 also serves as a means of conducting the heat of combustion to the cup even when the fuel level is too low to flood the lip 61.

In the form of Figures 7 and following, the fins 77 correspond to the fins 45 of Figures 2 and 3, and perform the same function. In addition, the extension 78 conducts heat to the cup from the flame as the prong is in contact with the flame and with the hot gases of combustion flowing out of the pot. We have omitted the recirculating ring from Figure 7. It will be understood that it may be employed, if desired.

We have also shown in connection with Figure 7, means for unitarily controlling the air supply to the space about the pot, and the tertiary air in relation to the rate of flow of the fuel. It will be understood that this tertiary air control may be employed, if desired, with all forms of our invention herein described.

We claim:

1. In a horizontal pot type burner, a burner pot having a circumferential wall with a plurality of air inlet apertures therein, a vaporizing cup located within said pot, means for directing a flow of liquid fuel to the interior of said cup and means for conducting heat to said cup, including a plurality of flanges extending downwardly from the bottom of the cup, the means for delivering the liquid fuel to the cup including a hollow stem extending downwardly from the cup, said stem being unitary with said downwardly extending flanges.

2. In a pot type horizontal burner, a horizontally axised pot having an open end, a centrally apertured flame ring partially closing said open end, and a circumferential wall with a plurality of air inlet apertures therein, a vaporizing cup

located within said pot, means for directing a flow of liquid fuel to the cup and means for conducting heat to the cup including a heat conducting element extending laterally from the cup a substantial distance along the path of outward movement of the heated gases and flame from the pot through said flame ring.

3. In a pot type horizontal burner, a horizontally axised pot having an open end, a centrally apertured flame ring partially closing said open end, and a circumferential wall with a plurality of air inlet apertures therein, a vaporizing cup located within said pot, means for directing a flow of liquid fuel to the cup and means for conducting heat to the cup including a heat conducting element extending from the cup along the path of outward movement of the heated gases and flame from the pot through said flame ring, said element being hollow and in communication with the interior of the cup.

4. In a pot type horizontal burner, a horizontally axised pot having an open end, a centrally apertured flame ring partially closing said open end, and a circumferential wall with a plurality of air inlet apertures therein, a vaporizing cup located within said pot, means for directing a flow of liquid fuel to the cup and means for conducting heat to the cup including a heat conducting element extending from the cup along the path of outward movement of the heated gases and flame from the pot through said flame ring, said element being hollow and in communication with the interior of the cup, and means for preventing the flow of liquid fuel from the cup to the interior of said element until the level of liquid fuel in the cup exceeds a predetermined height.

5. In a pot type burner, a pot having an open end, a centrally apertured flame ring partly closing said open end, and a circumferential wall with a plurality of air inlet apertures therein, a vaporizing cup located within said pot, means for directing a flow of liquid fuel to the cup, and means for conducting heat to the cup including a heat conducting projection extending from the cup along the path of flow of the heated gases and flame from the pot, said projection being unitary with the cup and of substantially smaller diameter than the cup, and extending along the axis of the aperture of the flame ring.

6. In a pot type burner, a pot having a circumferential wall with a plurality of air inlet apertures therein, a vaporizing cup located within said pot, means for directing a flow of liquid fuel to the cup, means for conducting heat to the cup including a unitary heat conducting projection extending from the cup, and a centrally apertured flame ring partially closing the mouth of the pot, said projection extending through the aperture of the flame ring.

7. In a pot type burner, a pot having a circumferential wall with a plurality of air inlet apertures therein, a vaporizing cup located within said pot, means for directing a flow of liquid fuel to the cup, means for conducting heat to the cup including a unitary heat conducting projection extending from the cup, and a centrally apertured flame ring partially closing the mouth of the pot, said projection extending through the aperture of the flame ring, and a centrally apertured recirculating ring, within the pot, and surrounding said projection.

8. As a new article of manufacture, a vaporizing cup, for pot type burners, including a cup element, a stem unitary therewith, said stem hav-

ing a fuel passage extending to the interior of the cup element and a plurality of unitary heat conducting flanges extending outwardly from said cup element and from said stem.

9. In a horizontal pot type burner, a sheet metal burner pot having a closed end wall, a circumferential side wall and an open end, said circumferential side wall having therein a plurality of air inlet apertures located at various distances from the end of the pot and distributed generally uniformly circumferentially about the pot, a vaporizing cup, located within said pot and including a cup bottom and a circumferential side wall, means for directing a flow of liquid fuel to the interior of said cup, and means for conducting heat to said cup including flange means extending downwardly from the bottom of the cup, the cup, including its bottom and side wall and said flanges, constituting a unitary metal member of substantially greater thickness than the gauge of the sheet metal of the burner pot.

10. As a new article of manufacture, a vaporizing cup adapted for use in hydroxylating burners, which includes an open topped cup body surrounded by an integral circumferential wall, a 25

stem, unitary with said body, having a bore in communication with the interior of the cup at a level adjacent the bottom of the cup, and heat conducting flanges extending downwardly from said body, said flanges being in the form of relatively thin sheets generally perpendicular to and unitary with the bottom of the cup.

11. As a new article of manufacture, a vaporizing cup adapted for use in hydroxylating burners, which includes an open topped cup body surrounded by an integral circumferential wall, a stem, unitary with said body, having a bore in communication with the interior of the cup at a level adjacent the bottom of the cup, heat conducting flanges extending downwardly from said body, said flanges being in the form of relatively thin sheets generally perpendicular to and unitary with the bottom of the cup, said stem extending downwardly from the bottom of the cup at a generally central point, said flanges radiating outwardly from said stem, and being in heat conducting relationship therewith.

BRUCE HAYTER.
STANLEY PERRY.
